UNITED STATES PATENT OFFICE.

CARL GIESECKE, OF BAD HARZBURG, GERMANY.

SHAFT-FURNACE.

1,399,297.

Specification of Letters Patent.

Patented Dec. 6, 1921.

Application filed March 27, 1917. Serial No. 157,741.

(GRANTED UNDER THE PROVISIONS OF THE ACT OF MARCH 3, 1921, 41 STAT. L., 1313.)

To all whom it may concern:

Be it known that I, CARL GIESECKE, engineer, a citizen of the German Republic, residing at Bad Harzburg, Germany, have 5 invented certain new and useful Improvements in Shaft-Furnaces, of which the following is a specification.

My present invention relates to shaft furnaces and in particular to shaft furnaces of 10 the type in which preliminarily shaped pieces are agglomerated. It is a principal object of my present invention to provide improvements in the construction of shaft furnaces of such a type whereby I am enabled not only to discharge the contents of 15 the furnace in a continuous and regular order but to remove the pieces which have been solidified by the action of the furnace heat, from the furnace without demolishing them 20 to any extent and also without producing any substantial dust formation due to levigation. It is a further object of my invention to provide improved means for mechanically discharging the treated contents 25 of the furnaces in a continuous and regular manner. It is a further object of my invention to provide improved means whereby the individual pieces treated within the furnace and which may have become joined 30 owing to a sintering of their surfaces, are mechanically separated from each other prior to or during the discharge.

With these and other objects in view, I give the furnace a construction whereby the 35 sintered pieces may be removed without compressing them and without any application of force. To this end, I construct the furnace so that the charges to be removed pass through a furnace space of increasing 40 sectional area. Further features of my invention will be specifically described herein-after.

In order to illustrate the novel structural features by means of which I may attain 45 these and other objects, I have shown some practical embodiments of my invention in the accompanying drawings, by way of example.

Figure 1 is an elevation, partly in section, 50 of a shaft furnace according to my invention. Fig. 2 is a plan view of some parts shown in Fig. 1. Fig. 3 is a view similar to Fig. 1, illustrating a modified construc-

tion of some of the parts. Fig. 4 is a view similar to Fig. 2, of a further modified construction. Fig. 5 is a view similar to Fig. 3, showing a modified construction of the clearing and lifting means. Fig. 6 is a fragmentary view, partly in section, of a furnace of a modified shape; and Fig. 7 shows, 60 in a plan view, another construction of a bottom plate.

Referring to the drawings, *a* is the furnace shaft and *b* a core extending vertically through that part of the furnace which is 65 normally charged with sintered pieces. The core *b* may consist of cast iron and I prefer to make the same hollow and to utilize the hollow space for the introduction of air into the interior of the furnace. In Fig. 1 I have 70 shown the outer furnace wall as being of substantially cylindrical shape but for its lower termination. In order to obtain an interior furnace space of gradually increasing sectional area, in downward direction, 75 the said core *b* may be of decreasing diameter toward the furnace bottom. As shown in Fig. 6, I may give the furnace shaft *a* the shape of a cone having its base coinciding with the furnace bottom. In such a 80 case, the core *b* may be cylindrical, or may also be of the shape of a cone, as shown in Fig. 6. The essential feature according to my present invention is that the interior furnace space as determined by the 85 diameters *D* and *d*, see Fig. 1 and Fig. 6, is of steadily increasing sectional area.

By this construction, those obstructions that normally oppose a ready discharge of the treated furnace contents, are reduced to 90 a minimum, and the production of unnecessary pressure is obviated thereby. This avoidance of pressure involves a reduction of friction whereby any undesirable demolition or levigation of the individual agglomerated pieces is prevented.

In order to obtain an effective closure at the open discharge end of the furnace and thereby to insure a regular discharge and prevent a casual rolling off of the larger 100 ball-like or roll-like pieces treated within the furnace heat, I provide for the formation of an annular pile immediately below the discharge opening of the furnace. To that end, I provide the furnace bottom 105 which is preferably slightly inclined to

ward the circumferential discharge opening, with a stowing ring or flange *i*. In the illustrated embodiment the furnace bottom is shown to be of the form of a disk or plate 5 *h* from which the circumferential stowing flange *i* projects upward and prevents the pieces lying immediately upon the disk from rolling off. As I have shown in Fig. 7 in a plan view, the stowing flange *i* need not be 10 continuous and may be composed of several parts. If desired the stowing flange *i* may be made adjustable.

The pieces thus accumulating in front of the stowing ring form a base layer for the 15 superposed layers of ball-like and roll-like pieces piling thereon and which are prevented by said comparatively stationary base layer from sliding off. In order to constantly remove from the pile the excess radially outward I provide revolving clearing members *f* as shown in Figs. 1 and 2. These clearing members may be of any approved structure, they are preferably mounted on a revoluble table *k* to which a revolving motion is transmitted 20 from any suitable source of power, by means of the worm gearing *m*, *n*, indicated in the drawings. By means of the revolving clearing device, a regular operation of the furnace can be obtained the discharging action 25 being thereby adjustable exactly in correspondence to the time occupied by the burning action upon a furnace charge. As shown in the drawings, the clearing members *f* are structures having an outer edge of a spiral curvature which exerts a pushing action 30 upon the portion to be displaced off the pile.

In order to automatically separate any adhering pieces prior to or during the dis- 40 charge, I have further provided a device whereby the continually sinking charge is periodically slightly raised and thereupon allowed to drop the dropping action produc- 45 ing the desired separation of any adhering pieces. To this end, the clearing members *f* are provided on their top with screw-like rising and abruptly terminating faces *c* formed by wedge-like bodies to which thus is allotted a dual function, viz. producing a 50 circumferential clearing motion by means of the edge faces *f* and a raising and dropping motion by means of the top faces *c*. While these bodies of dual function are revolving they produce a relative shifting movement 55 in alternate directions, of the pieces forming the furnace charge; and in conjunction with the sudden dropping motion the desired separation effect is obtained in an easy and effective manner.

60 The screw shaped raising or lifting faces *c*, instead of being disposed below the furnace mouth, may be located within the same.

In the embodiment illustrated in Fig. 3, the screw shaped lifting faces *c* are shown 65 to be mounted upon a cone *d* which facili-

tates the radial outward displacing motion of the furnace contents. In the modified construction shown in Fig. 4, the clearing faces *c* and the lifting faces *c* are formed on separate members arranged in alternate 70 order upon the supporting disk *h* which may also be of conical shape, such as shown in Fig. 3.

In the embodiment shown in Fig. 5, both motions, viz. the radial displacing motion 75 and the axial lifting motion, are produced by the members *g* which represent screw shaped bodies mounted upon a cone *l*. When the cone *l* is caused to revolve by means of the power transmitting gearing 80 *m*, *n*, the mass of the furnace contents resting upon the structures *l*, *g*, is axially raised and dropped and simultaneously displaced outward in radial direction, by means of the screw shaped faces *g* owing to their oblique 85 disposition.

From the description as given hereinbefore, it will be obvious that the scope of my invention is not to be restricted to the particular structural means shown in the draw- 90 ings by way of example; but that I may employ different structural means for obtaining the desired effects without thereby departing from the scope and spirit of my invention.

What I claim as my invention and desire 95 to secure by Letters Patent of the United States, is:—

1. In a device of the character set forth, the combination of a tubular member having a discharge opening at its lower end, 100 and a core disposed within that part of the member through which sintered pieces are caused to pass and also extending through said discharge opening, said core being of such a shape that the available member space increases in sectional area toward the discharge opening of the member.

2. A device of the character set forth comprising, in combination, a tubular member having a discharge opening at the lower end 110 thereof, said member provided with an interior space of steadily increasing sectional area toward said discharge opening, a core disposed within that part of the member through which sintered and extending pieces 115 are caused to pass, and a bottom member having a stowing rim extending within said discharge opening.

3. A device of the character set forth comprising, in combination, a tubular member having a discharge opening, a bottom below 120 said opening, a core disposed above said bottom and within that part of the member through which sintered pieces are caused to pass, said member and said core having such 125 relative shapes that the available space between them steadily increases in sectional area toward said discharge opening, and revoluble clearing means disposed above said bottom and below the discharge open- 130

ing and adapted to displacingly remove the treated charge through said discharge opening.

4. A device of the character set forth comprising,

5 in combination, a tubular member having a discharge opening at the lower end thereof, said member having an interior space of steadily increasing sectional area toward said discharge opening, a bottom be-

10 low said discharge opening having a stowing rim within said opening, and revoluble clearing means disposed above the level of said stowing rim and below the discharge opening and adapted to continually remove

15 a portion of the stowed charge by a displacing action through said discharge opening.

5. A device of the character set forth comprising,

in combination, a tubular member having a discharge opening at the lower end

20 thereof, said member having an interior space of steadily increasing sectional area toward said discharge opening, a bottom member below the discharge opening having a stowing rim extending within said

25 opening, and means for periodically raising and dropping the charge above said bottom.

6. A device of the character set forth comprising,

30 in combination, a tubular member having a discharge opening at the lower end thereof, said member having an interior space of steadily increasing sectional area toward said discharge opening, a core disposed within that part of the member

35 through which sintered pieces are caused to pass, a bottom member having a stowing rim extending within said discharge opening, and revoluble means disposed above the level of said stowing rim below the dis-

40 charge opening and adapted to periodically raise and drop the charge above said bottom.

7. A device of the character set forth comprising,

45 in combination, a tubular member having a discharge opening at the lower end thereof, said member having an interior space of steadily increasing sectional area toward said discharge opening, a bottom be-

50 low the discharge opening having a stowing rim extending within said discharge opening, revoluble clearing means disposed above the level of said stowing rim and adapted to continually remove a portion of the stowed charge by a displacing action

55 through said discharge opening, and revoluble means disposed above said bottom and adapted to periodically raise and drop the charge.

8. A shaft furnace of the character set

60 forth comprising,

in combination, a bottom plate below said opening, a stowing rim on said bottom plate and extending within said discharge opening, a core disposed within that part of the member

65 through which sintered pieces are caused to pass, said member and core being of such relative shapes that the available space between them steadily increases in sectional area toward said discharge opening, revo-

70 luble clearing means disposed above the level of said stowing rim and adapted to produce a radial displacing action upon the charge stowed within said discharge opening, and revoluble means disposed above said bottom

75 plate and adapted to periodically raise and drop the charge, whereby any adhering pieces of the sintered charge are caused to separate.

9. A device of the character set forth comprising,

in combination, a tubular member having a lower discharge opening, a bottom below said opening, a core disposed above said bottom and extending through that part of the member

80 through which sintered pieces are caused to pass, said member and core having such relative shapes that the available space between them steadily increases in sectional area toward said discharge opening, and revoluble means dis-

85 posed above said bottom and adapted to simultaneously produce a radial displacing action upon the stowed charge and an axial raising and dropping movement of the charge.

10. A device of the character set forth comprising,

in combination, a tubular member having a lower discharge opening, a bottom plate below said opening and having a stowing rim extending within said discharge

100 opening, a core disposed above said bottom plate and extending through that part of the member through which sintered pieces are caused to pass, said member and core

105 being of such relative shapes that the available space between them steadily increases in sectional area toward said discharge opening, and revoluble means disposed above the level of said stowing rim and adapted to simultaneously produce a radial

110 displacing action upon the stowed charge and an axial raising and dropping movement within the charge resting on said bottom plate.

In testimony whereof I have hereunto set my hand in presence of two subscribing witnesses.

CARL GIESECKE.
